BOBBIN HOLDING MEANS

Filed Feb. 14, 1945

UNITED STATES PATENT OFFICE

2,466,861

BOBBIN HOLDING MEANS

Burt A. Peterson, Rockford, Ill., assignor to Barber-Colman Company, Rockford, Ill., a corporation of Illinois

Application February 14, 1945, Serial No. 577,866

12 Claims. (Cl. 242—130)

1

The invention pertains in general to bobbin holders for use in textile mills, and has for a general aim the provision of bobbin holders for use with automatic bobbin winding machines in which the doffed bobbins are delivered directly to holders each adapted to support a group of bobbins whereby to facilitate handling of the bobbins.

In a more specific aspect the invention pertains to bobbin holding means of the pin board type and provides a plurality of individual holders for mounting upon a convenient supporting and carrying frame so as to form a sectional pin board.

With the foregoing in view, an important object of the invention is to provide a bobbin holder in the form of an elongated slide equipped with a series of supporting pins and constructed and arranged to be supported for sliding movement relative to suitable supporting and guiding means whether the latter form a part of a bobbin winding machine or a portable supporting and carrying frame.

A further object is to provide a bobbin holder of the character indicated which is light in weight yet strong, rugged and durable and capable of being manufactured at a low cost.

Another object is to provide a pin board comprising a supporting frame and a plurality of bobbin holders each adapted to receive and support a plurality of bobbins and constructed and arranged for quick and easy application to or removal from the frame.

The objects of the invention thus set forth are attained by the construction and arrangement shown by way of illustration in the accompanying drawings forming part hereof wherein I have shown a plurality of bobbin holders forming a part of a sectional pin board. The application of the holders to guiding and supporting means forming a part of a bobbin winding machine is disclosed and claimed in my copending application Ser. No. 577,865, filed February 14, 1945.

In the drawings, Figure 1 is a perspective view of a sectional pin board embodying my invention.

Fig. 2 is a fragmentary transverse sectional detail view showing detent means yieldably retaining bobbin holder slides in position on the supporting frame of the pin board.

Fig. 3 is a transverse longitudinal section taken approximately in the line of 3—3 of Fig. 2.

Fig. 4 is a fragmentary detail view in plan illustrating the operation of placing a bobbin holder slide onto the supporting frame.

In the present exemplary embodiment of the invention a plurality of the novel bobbin holders

2

7 are shown for use with or mounting upon a common supporting frame 8 to form a sectional pin board. Each holder comprises an elongated slide 9 made of sheet metal and consisting of a flat 5 narrow plate or bar with flanged opposite edge portions providing slide members 10 preferably shaped to form opposed grooves or channels 11. These edge portions perform the added function of stiffening and strengthening the slides thereby 10 permitting the use of metal of relatively light gauge which is desirable both from the standpoint of cost and weight.

Each slide is equipped with a series of bobbin 15 supporting elements or devices herein in the form of pins 12 mounted in uniformly spaced parallel relation along the slide bar centrally thereof. As shown in Fig. 3 the pins are preferably made hollow or tubular for the sake of weight reduction and each comprises a base portion 13 and a tip 14 of relatively smaller diameter. The base portion 13 of the pin has an external bore fitting 20 relatively snugly with respect to a metallic sleeve 15 with which the butt ends of the bobbins are commonly equipped.

The pins are advantageously mounted in the 25 slide bar 9 by a swaging operation. For this purpose countersunk holes are formed along the bar, and annular flanges 16 projecting axially from the base portions 13 of the pins are inserted through the holes and then expanded outwardly into firm binding engagement with the slide bar. In such expansion of the flanges 16 the shoulders 30 17 of the pins are drawn downwardly toward the slide bar and this action is utilized to clamp bobbin retaining clips 18 firmly in position. Each clip is made from a thin piece of sheet metal to 35 form an apertured base 19 which is interposed between the pin shoulder 17 and the top face of the bar. At one end the base 19 carries an upright arm 20 for yieldably engaging between adjacent rings 21 on the bobbin. To position each clip relative to the slide, a lug 22 depends into a slot 23 in the bar.

40 The supporting frame 8 is constructed to provide guide members 24 for interfitting engagement with the slides, and in view of the channel formation of the slide members 10 the guide members are in the form of flat flanges protruding 45 outwardly from channel shaped guide bars 25.

The latter also constitute frame members, being rigidly secured as by welding to cross frame members 26 which are likewise of channel form for stiffening and strengthening purposes. It 50 will be observed that the flanges in addition to

forming the guide members 24 lend strength and rigidity to the frames.

To facilitate movement of the slides onto the frame bars 25 the ends of the slide members 19 may be cut back a short distance from the ends of the slide bars as indicated at 27 so as to reduce the width of the ends of the slide bars substantially to the width of the guide bars. Also the bottom sides of the channels 11 may be rounded slightly as shown at 28 for coaction with the ends of the upright channel walls of the guide bars in guiding the slides onto the guide bars.

To enable the bobbin holders to be set on end without resting upon or interfering with the end bobbins, the slides are preferably provided at opposite ends with rests in the form of flanges 29 integral with the top plates 9 of the slides. These rests are of special utility in the use of the holders in automatic bobbin winding machines, as disclosed in my said copending application.

For purposes of retaining the holder 7 yieldably in position upon the frame 8 each slide is provided with a block 30 (Figs. 2 and 3) for coaction with a spring detent 31 on the supporting frame. The block is rigidly fastened to the underside of the slide bar centrally thereof and is recessed to receive a ball 32 mounted in a cup 33 and urged outwardly by a spring 34. The cup 33 may advantageously be located within and therefore protected by the channel formation of the intermediate ones of the cross bars 26.

It will be seen that my invention provides bobbin holders especially adapted for use in the transfer of bobbins in groups from a bobbin winding machine to a storage device such as a pin board. Since the wound bobbins are supported in a single row upon individual holders they are capable of easy and convenient inspection. Moreover, such holders provide for the easy handling of the bobbins without the necessity of touching the same which is a substantial advantage especially in the case of rayon yarn or other filament yarns. Finally, the particular construction employed provides a pin board of light weight yet very rugged and durable.

I claim as my invention:

1. A bobbin holder adapted to be mounted upon a support providing spaced parallel guides, said holder comprising a slide bar flanged longitudinally thereof to stiffen the bar and to form complementary slide members for interfitting engagement with said spaced parallel guides, and a series of bobbin supporting elements rigid with said bar.

2. A bobbin holder adapted to be slid endwise relative to a support providing spaced parallel guide elements, said holder comprising a slide bar having stiffening flanges at its opposite side edges shaped to form opposed guides for interfitting engagement with said guide elements, and bobbin supporting elements on said bar.

3. A bobbin holder to be slid endwise relative to a support providing spaced parallel guide members, said holder comprising a slide bar of sheet metal having channel shaped edge portions forming slide members for coaction with said guide members, and a series of bobbin supporting devices rigidly secured to said slide bar in longitudinally spaced relation.

4. A pin board having a supporting frame with a plurality of guide bars for slidably receiving elongated bobbin holders having elongated slide members, said frame having a plurality of cross

bars and said guide bars being rigidly secured to said crossbars upon one side thereof, and said guide bars having stiffening flanges offset from the aforesaid side of the cross bars to form guide members for interfitting engagement with the slide members of the bobbin holders to permit endwise sliding movement of the slide members.

5. A pin board comprising, in combination, a supporting frame providing a plurality of spaced parallel guides, bobbin holders having parallel slide members arranged for interfitting endwise sliding engagement with said guide members, and means yieldably retaining the bobbin holders against endwise movement upon the frame.

6. A pin board comprising, in combination, a supporting frame having a plurality of cross members and a plurality of spaced parallel guide bars mounted on said cross members and providing guide members for interfitting engagement with complementary slide members of elongated bobbin holders, and detent means on one of said cross members on the frame yieldably retaining the bobbin holder in position thereon.

7. A pin board comprising, in combination, a supporting frame providing a plurality of spaced parallel guide bars and a plurality of cross bars, said guide bars providing parallel guide members for interfitting engagement with complementary slide members of a plurality of elongated bobbin holders, one of said cross bars being of channel form and detent means mounted in the channel of said one cross bar for coaction with the bobbin holder slide members to retain them in position upon the frame.

8. A bobbin holder having a supporting plate with holes at spaced points, bobbin supporting pins having base portions providing shoulders, annular flanges depending axially from said shoulders and inserted through the holes in the plates, said flanges being expanded to hold the pins firmly in position on the plate, and bobbin holding clips interposed between the plate and said shoulders.

9. A bobbin holder for detachable mounting upon a support providing a pair of spaced parallel guide elements, said holder comprising an elongated member having reversely bent edge portions forming channel shaped slides engageable with the guide elements on the support, and bobbin holding devices spaced apart on said member.

10. A device for supporting bobbin holders having opposed parallel channel shaped slide members, said device comprising a supporting frame having a plurality of cross members and a plurality of guide members spaced above the cross members for interfitting engagement with the bobbin holder slide members.

11. A pin board comprising a rectangular supporting frame having a plurality of parallel cross bars, a plurality of guide bars rigidly secured in spaced parallel relation on said cross bars and providing elongated guides in offset relation to said cross bars, and a plurality of bobbin holders comprising elongated slides engageable with said guides in a relative longitudinal movement of the slides and guides, said slides and guides interfitting to hold the slides against movement transversely of the guides, each of said slides having a plurality of bobbin supporting elements mounted thereon in longitudinally spaced relation.

12. A pin board comprising a rectangular supporting frame having a plurality of parallel cross bars, a plurality of guide bars rigidly secured in spaced parallel relation on said cross bars

and providing elongated guides in offset relation to said cross bars, and a plurality of bobbin holders comprising elongated slides engageable with said guides in a relative longitudinal movement of the slides and guides, said slides and guides interfitting to hold the slides against movement transversely of the guides, each of said slides having a plurality of bobbin supporting elements mounted thereon in longitudinally spaced relation and each including means for 10 yieldably retaining the bobbin in position thereon.
